MOTION PICTURE PROJECTOR FOR FILM CARTRIDGES OR THE LIKE

Dianne B. Ainslie, Rochester, N.Y., assignor to Eastman
Kodak Company, Rochester, N.Y., a corporation of
New Jersey

Filed June 27, 1969, Ser. No. 17,920

Term of patent 14 years

Int. Cl. D16—04

U.S. Cl. D61—1

FIG. 1

FIG. 2

FIG. 1 is a perspective view of the front, top and one side of a motion picture projector for film cartridges in accordance with the present invention.

FIG. 2 is a perspective view showing the rear, top and other side of the motion picture projector for film cartridges of FIG. 1.

I claim:

The ornamental design for a motion picture projector for film cartridges or the like, as shown.
